HYDRAULICALLY OPERATED COMPRESSOR

Otto J. Schemmel, Chicago, Ill.

Application January 22, 1954, Serial No. 405,599

3 Claims. (Cl. 230—53)

The present invention is directed to a power translating device, and is primarily concerned with an improved hydraulically operated compressor.

A compressor built according to the present invention finds particular use in the field of refrigeration, particularly in refrigeration and air conditioning equipment designed for installation in automobiles and trucks. In such installations, it is necessary to provide a compact, readily portable unit which can be operated at high efficiency from a portion of an internal combustion engine.

An object of the present invention is to provide an improved power translating device, and more specifically, an improved hydraulically operated compressor mechanism.

Another object of the invention is to provide a readily portable compressor unit particularly adapted for refrigeration systems associated with motor driven vehicles.

Still another object of the invention is to provide a highly efficient, compact compressor unit, and to provide such a unit with a dual drive system whereby the compressor may be operated from an internal combustion engine or from a secondary source of power.

The meaning and importance of this stated object will be better understood from the following explanation:

Refrigerated trucks of that type in which the refrigerating operation is produced by the use of the heat cycle, necessarily include in their equipment power driven compressors for compressing and liquifying the refrigerant which is then cooled by suitable means such as air radiators, and thereafter expanded in the expansion unit to produce the refrigerating action. The present invention concerns itself especially with an improved form of such power driven compressor. The arrangement is such that during normal operation on the road the power needed to run such compressor is derived from the power plant of the refrigerated truck. It is however, highly desirable to be able to operate the refrigerating compressor to produce the desired cooling effect while the truck is laying over for extended intervals at terminals or delivery or loading stations. In many cases, also, it is desirable to pre-cool the refrigerated space prior to loading, so that time may be saved after the loading operation has been completed, or, in some cases to refrigerate the loaded space prior to starting the travel of the truck with its load. In all such cases the needed refrigerating action is produced while the truck is standing idle.

When provision is made only for operation of the refrigeration compressor by power derived from the truck's power plant it is evident that it would be necessary to keep the truck's power plant in operation during such layover or loading or unloading intervals. Since the amount of power needed for operation of the refrigerating compressor is only a small percent of the capacity of the truck's power plant it is evident that the operation of the truck's power plant only for the refrigerating action, and for extended intervals of time, would be a highly inefficient and consequently expensive operation. Additionally it would entail needless operation and wear of the

truck's power plant. The operation of the internal combustion engine of the truck's power plant while standing within an enclosed space, such as a station or terminal, also presents elements of danger to health, as well as fire hazards, etc.

It is also noted that when the truck is of that type including a so-called "tractor" unit to which the truck body is removably connected during normal road running, the detachment of such body from the "tractor" unit, as is generally done during extended layovers, makes the tractor power plant unavailable as a source of power for refrigeration at such times.

To meet the foregoing and like conditions, it has been a widely adopted practice to drive the refrigerating compressor by a small specially provided internal combustion engine. Such arrangements present many objections from installation as well as operational standpoints. The use of electric motor drives for such truck refrigerating compressors, using current from the truck's storage battery

has been proposed. This scheme, however presents the serious objection that operation of the refrigerating compressor by battery current alone, for an extended interval of ten to fifteen hours, or more, in a terminal station would entail the provision of battery capacity far beyond the normal requirements for truck operation, with corresponding high first cost and the need of carrying a very large dead load during truck travel. It is also pointed out that even should it be decided to use such electric motor drive for the refrigeration compressor, operating it off of the usual truck power motor driven electric generator during normal road running operations, such electric motor compressor could not be directly fed with electricity from the available electricity service supplies at the terminals in order to avoid operation off of the truck's battery. This is true since the usual truck battery and electrical equipment are designed for six or twelve volt or similar low voltage D. C. operation, whereas the usual electricity services are of either 110 or 115 volt A. C. rating.

Accordingly it is a prime object and feature of the present invention to provide a refrigeration compressor unit and system of operation which is admirably adapted to meet the normal road running operating conditions of the refrigerated truck, as well as the very special conditions imposed during the refrigerating operation when the truck is standing idle for an extended time at a terminal or other station. To this end I have provided a refrigeration compressor unit which includes a motor driven by oil under pressure and driving the compressor elements by which the refrigerant is compressed. The truck system includes this unit and also suitable piping connections for supply of the oil under pressure from a pumping source and return of the low pressure oil to the pumping source. During normal road operation the pressure and return oil lines are connected to a specially provided oil pump which is driven by the truck's power motor, as by a belt drive from the fan belt shaft; or, alternatively, such pressure and return oil lines may be connected to the pressure and return sides of the oil pump of the truck's power engine itself. In case of provision of such special oil pump it may be readily accommodated under the engine hood. I then also provide a supplementary electric motor driven oil pump, having its pressure and return oil lines connected to the pressure and return oil lines for the oil driven refrigerant compressor, under proper valve control so that the refrigerant compressor may be operated by pressure oil supplied either by the truck's engine oil circulating system and returned to such system for re-circulation, or by such special belt driven pump, for normal road running conditions; or so that the refrigerant compressor may be operated by pressure oil supplied by such electric motor driven oil pump and re-

turned to such pump for repeated re-circulation. Such supplementary electric motor driven oil pump may be provided with an electric motor of the A. C. type, intended for operation on the usual 10-115 volt A. C. service supply which is almost universally available.

By my novel arrangement outlined above it is possible to use the power supply available in the conventional form of truck power plant for normal road operation, and substantially without change of costly or objectionable nature. It is also possible to switch over to "lay over" refrigerating operation by merely plugging an electric line from the supplementary electric motor driven oil pump into any available service outlet socket at the terminal or other layover point.

A further description of the present invention will be made in conjunction with the attached sheets of drawings which illustrate a preferred embodiment of the invention.

Figure 1 is a view in elevation and partially in cross section illustrating a hydraulically operated compressor embodying the principles of the present invention;

Figure 2 is a fragmentary cross-sectional view, with parts in elevation, of the control mechanism employed in the compressor, this view being taken substantially along the line 2-2 of Figure 4;

Figure 3 is a cross-sectional view, with parts in elevation, taken substantially along the line 3-3 of Figure 4;

Figure 4 is a cross-sectional plan view taken substantially along the line 4-4 of Figure 2;

Figure 5 is a fragmentary back view, with parts in elevation, of the compressor unit;

Figure 6 is a front elevational view of a modified form of the apparatus;

Figure 7 illustrates schematically the manner in which the compressor unit may be driven selectively from an internal combustion engine and from an outside source of power;

Figure 8 illustrates schematically the hydraulic control system illustrated in Figures 1-5 of the drawings; and

Figure 9 is a view in perspective of a truck equipped with a compressor unit of the type described.

In Figure 1, reference numeral 10 indicates generally a metallic casing which includes a space serving as a sump or oil reservoir 11. A housing 12 is secured to the casing 10 by means of bolts 13 extending through flange portions 14 of the housing 12.

The bolts 13 are received in a flange portion 16 provided on a second housing 17 which encloses the operating members of the hydraulically controlled operating system.

The housing 12 may be provided with spaced fins 19 along its outer periphery to aid in dissipating heat from the assembly.

The housing 12 is suitably machined to provide a plurality of cylinders 21 and 22 which receive a pair of hollow pistons 23 and 24 in sliding engagement. The pistons 23 and 24 may be provided with usual piston rings 26 as shown in Figure 1.

Secured to the top of the housing 12 is a cover plate 27 which receives a pair of outlets 28 and 29 in threaded engagement, to direct the compressed air or other fluid from the cylinders into the mechanisms with which the compressor is associated. It will be understood that the housing 12 is also provided with inlet means and valves for directing the fluid into the cylinders 21 and 22 at the appropriate time during the travel of the pistons 23 and 24 to obtain adequate compression of the air during the piston strokes.

Each of the pistons 23 and 24 has wrist pins 31 and 32 extending therethrough, the wrist pins receiving a pair of rods 33 and 34, respectively. Also secured to the wrist pins 31 and 32 are a pair of racks 36 and 37. Disposed between the racks 36 and 37 and arranged to be driven by movement of the racks is a pinion 38 secured to a shaft 39. One end of the shaft 39 is journaled for rotation in

a bearing 40. The rotation of the shaft 39 by the reciprocatory movement of the pistons controls the operation of the hydraulic system, as will hereinafter appear.

The rods 33 and 34 are slidably received in a pair of sleeves 41 and 42, respectively, the sleeves being threaded into suitable recesses provided in the base of the housing 17.

The hydraulic control mechanism is perhaps best illustrated in Figures 2 to 4 of the drawings, and as illustrated, the system may include a reciprocating valve member 44 having a pair of ports 46 and 47 extending therethrough. The valve member 44 is recessed centrally and is machined to provide a plurality of teeth 48 which are arranged to mesh with the teeth of a pinion 49 fixedly secured to a shaft 51.

The pinion 49 also meshes with a plurality of teeth 52 formed in a slide member 53, as best illustrated in Figure 2. This slide member 53 operates the valve mechanisms, as will be explained more fully.

A pair of vertically extending passageways 56 and 57 are formed in the housing 17 below the sleeve 41 and a similar set of passageways 58 and 59 are formed in the housing below the sleeve 42. When the valve member 44 is in the position illustrated in the drawings, the passageway 56 communicates with a horizontally extending bore 61 through the port 46. A second horizontally extending bore 62 is arranged to communicate with the passageway 57, when the valve member 44 is shifted to the right, as viewed in Figure 2. Similarly, a pair of horizontally extending bores 63 and 64 are associated with the passageways 58 and 59 of the other half of the mechanism. In the illustrated position of the valve member 44, the bore 63 communicates with the passageway 58 through the port 47. When the valve member 44 shifts, the port 47 establishes communication between the bore 64 and the passageway 59.

As best illustrated in Figures 2 and 3, the hydraulic fluid, which will normally be oil, is introduced into one of a pair of inlet lines 66 and 67 disposed at opposite ends of the casing. The oil entering through the inlet 66 flows past a compressed helical spring 69 into a horizontally extending port 71, and then through an angularly disposed passageway 72 which connects the port 71 with bore 61 (see Figures 3 and 5). Similarly, a second horizontally disposed port 74 and an angularly disposed passageway 76 direct oil into the bore 64.

Referring to Figure 3, it will be seen that the hydraulic control system also includes a valve member having a tapered valve seat 77 which is normally urged into seating relation with the end of a cylinder 78 by the action of the spring 69. The valve element also includes a rod 79 on which a collar 80 is secured.

As the pistons 23 and 24 are reciprocated, the valve will be opened and closed once during each reciprocatory cycle. The valve member 77 is unseated at the time that the piston 23 is at its lowest vertical position. In this position, an operating pin 81 secured to an arm 82 extending from the rack 36 engages the pin 79 and forces the collar 80 into a position where it closes off a drain port 83 leading back to the oil reservoir. The oil, however, is able to flow past the valve seat 77 into a conduit 84 and through a port 86 (Figure 2) to thereby supply oil under pressure against one end of the slide member 53.

The piston 24 has an identical operating mechanism including a pin 87 which is arranged to open and close a similar valve element in the opposite end of the assembly. The valve is opened and closed by the action of a second operating pin 88 secured to an arm 89 extending from the rack 37. When the pin 87 is depressed, the oil under pressure flows to the opposite side of the slide 53 through a port 91 and communicates with a conduit 92 (Figures 1 and 4).

The operation of the device shown in Figures 1 to 5 has been simplified somewhat in the schematic showing of Figure 8. The showing in that figure represents the

position of the assembly at the time that the piston 23 is commencing to rise and the piston 24 is going down. In this position, oil under pressure enters through the line 66, causing oil to flow through the passageways 71, 72, and 61 through the port 46 in the sliding valve member 44, into the passageway 56 and then to the base of the rod 33 which is associated with the piston 23. At the same time, oil is being forced out of the other half of the compressor, the piston 24 and the rod 34 forcing the oil from the sleeve 42 through the passageway 58, the port 47 in the valve 44, and into a drain leading to the reservoir.

During the time the piston 23 is near its lowermost position, the valve 77 is unseated, thereby closing off the drain 83 and permitting oil flow through the passage 86 against the end of the slide member 53. During this interval, oil is discharged from the opposite end of the slide member 53 through the outlet passage 91.

Oil is continuously introduced in this manner until such time as the piston 23 reaches the upper position of its stroke and the piston 24 reaches its lowest position. When this occurs, the actuating pin 88 depresses the operating pin 87, so that oil commences to be discharged from the left side of the slide member 53 as viewed in Figure 8. At this time, the difference in pressure on opposite sides of the slide member 53 causes the slide member 53 to commence moving to the left, as seen in Figure 8. The rotation of the shaft 51 by the movement of the slide member 53 in engagement with the pinion 49 shifts the position of the slide valve 44 into a position where oil under pressure is introduced into the sleeve 42 to raise the piston 24, and oil is discharged from the sleeve 41 as the piston 23 goes down.

An alternative form of the invention makes use of gearing to translate the vertical movement of the pistons into the horizontal movement of the reciprocating valve member 44. In this form of the invention, the hydraulic control system is substantially eliminated, except for the pinion 49, the slide valve member 44 and the slide member 53.

The gearing is best illustrated in Figure 6 of the drawings which illustrates a relatively small gear 94 secured to the shaft 39 upon which the pinion 38 is located, and an idler gear 96 meshing with the gear 94. The idler gear 96 meshes with a larger gear 97 which floats on the shaft 51. Secured to the gear 97 are a pair of stop pins 98 and 99 arranged to engage a finger 101 keyed or otherwise fixedly secured to the shaft 51.

The gears 96 and 94 are also interconnected by an assembly which includes a pin 102 pivotally supported at the gear 97 by a pivot pin 103. The pin 102 is slidably received within a rotatable nub 104 mounted on the gear 96. A helical spring 106 extends between the pin 103 and the nub 104.

From Figure 6 it will be seen that the gear 97 is rotated in a counterclockwise direction by rotation of the gear 96 in a clockwise direction. The spring 106 is compressed until it reaches an over-the-center position, and at that time, the spring 106 expands, causing the stop pin 98 to strike the finger 101 and thereby rotate the shaft 51 on which the pinion 49 is located. This movement of the pinion 49 shifts the reciprocating valve member 44 from one position to its other position thereby reversing the flow of the hydraulic fluid between the cylinders. In effect, there is provided a lost motion connection between the movement of the pistons and the slide member 44.

Figures 7 and 9 illustrate one manner in which the compressor assembly of the present invention can be employed for refrigeration systems in trucks. As shown in these two figures, a compressor unit 110 may be connected across a discharge line 111 and return line 112 of a pair of pumps 113 and 114 operating in parallel. The pump 113 is arranged to be driven by an electric motor 115 as shown in Figure 7. The pump 114, on the other hand, is arranged to be driven from a pulley 116 and a

belt 117 extending from a source of power on the internal combustion engine, such as the fan belt drive.

For convenience, the engine operated pump 114 may be located immediately adjacent the engine as shown in Figure 9 and the electrically driven pump 113 with the motor 115 may be enclosed in a box readily accessible from the outside of the truck. Hence, it becomes a relatively simple matter to drive the compressor from the electrically driven pump 113 when the truck is in a garage by merely extending power lines to the motor 115.

From the foregoing it will be appreciated that the present invention provides a relatively simple, compact compressor unit particularly suitable for use in refrigeration systems for trucks. The unit needs very little maintenance and is highly efficient when compared to other types of compressors.

It will be evident that various modifications can be made to the above described apparatus without departing from the scope of the present invention.

I claim:

1. A pumping unit including in combination a pair of main cylinders having floors, a plunger reciprocably mounted in each cylinder, a rock element, means to journal said rock element for rocking movement, connections between the rock element and both plungers, said connections being constituted for simultaneous reciprocating movements of the plungers in their cylinders in opposite directions towards and from the floors of the cylinders, conduits in communication with each cylinder adjacent to the floor thereof, a pressure fluid supply conduit, a fluid release conduit, a main valve casing having a valve space, a reciprocable main valve member reciprocable in said valve space between a first position and a second position, pressure fluid and release fluid passages between the pressure fluid supply conduit and the fluid release conduit respectively and said main valve casing space, cylinder fluid passages between the conduits of each cylinder and said main valve casing space, there being fluid passages in said reciprocable main valve, said passages of the main valve and the points of connection of the pressure fluid supply passage and the fluid release passage with the valve casing space, and the points of connection of the cylinder passages of the two cylinders with said valve casing space, being so related that when the main valve is in said first defined position the cylinder passage of one cylinder is in communication with the pressure fluid passage only, and the cylinder passage of the other cylinder is in communication with the release fluid passage only, and that when the main valve is in said second defined position the cylinder passage of the first defined cylinder is in communication with the release fluid passage only, and the cylinder passage of the second defined cylinder is in communication with the pressure fluid passage only, together with means to reciprocate the main valve synchronously with the reciprocations of the plungers in the cylinders, said means comprising a reciprocable main-valve-actuator, a cylindrical space wherein said main-valve-actuator is reciprocably mounted, valve actuator fluid passages individually in fluid connection with the end portions of said cylindrical space, a valve chamber for each actuator fluid passage and in fluid connection with such passage, each such valve chamber corresponding to one of the main cylinders first mentioned, pressure fluid and release fluid ports in fluid connection with each such valve chamber, the pressure fluid ports communicating with the pressure fluid supply conduit and the release fluid ports communicating with the fluid release conduit respectively, a reciprocable valve member in connection with each valve chamber and including a valve element for the pressure fluid port of such chamber and a valve element for the release fluid port of such chamber, each such reciprocable valve member being constituted for sealing non-engagement of its release fluid port valve element with the fluid release port of such valve chamber when its pressure fluid valve ele-

ment is in sealing engagement with such pressure fluid port of such valve chamber, spring means normally urging each such valve member to position to engage the pressure fluid valve element into sealing engagement with the pressure fluid port of such valve chamber and with the release fluid port valve element of such valve member in sealing non-engagement with the fluid release port of such valve chamber, actuating means in connection with each plunger for actuating engagement with the reciprocable valve member of the valve chamber corresponding to such plunger, each such actuating means being constituted for actuating movement of such valve member against the urge of its spring during reciprocating travel of such plunger during the end portion of the plunger reciprocating movement at one end of the reciprocating travel of such plunger in its cylinder, and means to reciprocate the main valve member synchronously with the reciprocations of the main-valve-actuator.

2. Means as defined in claim 1, wherein the valve element for the pressure fluid port comprises a poppet type valve, and wherein the valve element for the release fluid port comprises a slide type valve, and wherein said valve elements are spaced and proportioned to produce opening of the release fluid port prior to seating of the poppet type valve against the pressure fluid port, and wherein

15

10

20

25

spring means normally retains the valve member in position with its poppet type valve element sealed against the pressure fluid port, and with its slide type valve element in non-sealing position with respect to the release fluid port.

3. Means as defined in claim 1, wherein the means to reciprocate the main valve member synchronously with the reciprocations of the main-valve-actuator comprises opposing rack elements on the main valve member and on the main-valve-actuator, together with a pinion meshing with both said rack elements, and means to journal said pinion for rotation about a fixed axis.
